UNITED STATES PATENT OFFICE.

EDWARD F. DUNNE, JR., OF MORRISTOWN, NEW JERSEY, ASSIGNOR TO WIREBOUNDS PATENTS COMPANY, A CORPORATION OF MAINE.

MACHINE FOR USE IN MAKING BOXES.

Application filed November 7, 1921. Serial No. 513,529.

To all whom it may concern:

Be it known that I, EDWARD F. DUNNE, Jr., a citizen of the United States, and a resident of Morristown, county of Morris, 5 and State of New Jersey, have invented new and useful Improvements in Machines for Use in Making Boxes, of which the following is a specification.

This invention relates to machines for 10 use in making boxes, crates, box or crate blanks or parts thereof, and more particularly to machines for use in making wire bound boxes, crates, box or crate blanks and the like.

15 Among other objects, the invention is intended to provide a machine of the class described in which fastener-setting mechanism operates upon continuously moving work and to provide such a machine with 20 mechanism for controllably positioning the fasteners in the work.

The invention will be best understood by reference to one illustrative embodiment thereof shown in the accompanying drawings 25 in which:

Fig. 1 is a side elevation of a box blank machine embodying the invention.

Fig. 2 is a sectional view taken on the line A—A of Fig. 1.

30 Fig. 3 is an end elevation seen from B—B in Fig. 1.

Fig. 4 is an enlarged cross sectional view 35 of one of the conveyer chains showing a staple positioning block secured thereto; said view being taken on the line C—C of Fig. 1.

Fig. 5 is an enlarged top plan view of the mechanism for driving the conveyer chains.

Fig. 6 is an enlarged top plan view of 40 a portion of the conveyer chain sprocket shaft at the delivery end of the machine and the operating gear therefor.

Fig. 7 is a sectional view taken on the line D—D of Fig. 6.

45 Fig. 8 is an enlarged top plan view of a portion of one of the conveyer chains showing the staple positioning blocks and the reciprocating pawl for propulsively engaging the blocks.

50 Fig. 9 is a side elevation of the same.

The present invention is directed to improvements in the type of machine disclosed in the application of Osceola C. Thompson, Serial No. 375,195, filed April 20, 1920, 55 which consists generally of a gang of fas-

tener-setting mechanisms operable to apply binding wire to box parts presented thereto in properly assembled relation by work-forwarding means, the work being fed continuously beneath the fastener-setting mechanisms which operate at intervals to drive fasteners into the moving work, and mechanism for automatically severing the binding wire between successive work assemblies. The improvements consist in providing such a machine with mechanism for controllably positioning fasteners at selected points in the work.

In the illustrative machine, the work-forwarding means comprises the endless conveyer chains 1 appropriately formed to receive cleats *c* and sheets of side material *s* for box or crate blanks and spacer blocks 2 adjustably secured to flanges 3 of the chains 1 for spacing the cleats *c* and sheets *s* of adjacent sections of a blank and for spacing successive blanks. Conveyer chains 1 run in channel guides 4 and pass over driven sprocket wheels 5 on shaft 6 at the delivery end of the machine and over idler sprocket wheels 7 on shaft 8 at the receiving end of the machine, said shafts 6 and 8 being journaled in suitable bearings in the frames 9 at either side of the machine, which frames are rigidly connected and supported by cross frame members 10. The chains 1 comprising individual links may be adjustable laterally to accommodate different sized boxes and the shaft 8 may be adjustable toward and from shaft 6 to accommodate the removal or insertion of individual chain links to shorten or lengthen the conveyer chains 1.

Sections of the cleats and sheets for a box blank or blanks are assembled in proper spaced relationship on the conveyor chains 1 between spacer blocks 2 and advanced beneath staplers 11 which connect said sections with binding wire by driving staples over the wires, through the sheets and into or through the cleats. Additional binding wires are or may be stapled to the sheets alone and the staples clinched on their under sides.

The binding wires 12 which are carried by suitable supply reels 13 and pass over rollers 14 are fed under rollers 15 at the feet of the stapler bodies and are pulled along by reason of their attachment to the work at preceding points.

The conveyer chains 1 are advanced continuously through a feed mechanism comprising sprocket wheel 16 keyed to a main shaft 17, sprocket chain 18, sprocket wheel 19 carried by a sleeve 20 on stud 21 suitably fastened to the frame of the machine, and spur gears 22, 23, 24, 25, 26 and 27, spur gear 27 being revolubly mounted on sprocket shaft 6 and having secured to its inner rim a series of pawls 28 adapted to engage a ratchet 29 keyed to shaft 6. This arrangement permits the shaft 6 and conveyer chains 1 to be moved faster, at intervals, than gear 27, for the purpose hereinafter explained. In the illustrative machine, the reduction gears are preferably proportioned and arranged to move the conveyer chains 1 approximately two inches per revolution of the main shaft, but it will be understood that the feed mechanism may be proportioned and arranged to produce a longer or shorter movement of the conveyer chains per revolution of the main shaft without departing from the invention.

In the illustrative machine the staplers 11 are carried by a carriage 30 which is reciprocable longitudinally of the work in guides 31 of the main frames 9. The individual staplers 11 which are adapted to form and drive a staple upon each revolution of the main shaft 17 may be of any suitable type, for instance, of the type disclosed in said application of Osceola C. Thompson above referred to, and are mounted on a cross head 32 set in the side frames of the carriage 30 and are operated by the vertically reciprocating cross head 33 slidably mounted in guides 34 of the side frames of the carriage 30, all as illustrated and described in said application above referred to.

Cross head 33 is reciprocated vertically through pitman 35 and eccentric 36 on the main shaft, there being similar operating mechanisms at either side of the machine.

Staple wire 37 from which the staples are formed is fed to the staplers 11 from suitable supply reels 38 over rollers 39 and between pairs of feed rollers (not shown), carried by shafts (not shown) journaled in the side frames of the carriage 30, said feed rollers being operated by a ratchet and pawl mechanism 40 through pitman 41 and eccentric 42 of the main shaft, all as illustrated and described in said application of Osceola C. Thompson above referred to.

The stapler carriage 30 is moved with the work during a stapling operation by means of a cam 43 on the main shaft 17 operating on a roller 44 carried at one end of a bell crank lever 45 pivoted at 46 to the frame of the machine the other end of which is pivotally secured to a bracket 47 carried by the carriage 30 so that when the roller 44 is raised by the cam 43, the carriage 30 will be advanced with the work.

The cam 43 and the lever 45 are so formed, adjusted and correlated with respect to the operation of the staplers 11 and the work-feeding mechanism that the carriage 30 is preferably advanced synchronously with the work during the lower half of the cycle of operation of the staplers during which time staples are driven into the work and is free to return to initial position through a spring 48 during the upper half of the cycle of operation of the staplers. Thus in the illustrative machine in which the work-forwarding chains 1 are advanced approximately two inches per revolution of the main shaft 17 the staplers will move with the work approximately one inch and then return one inch to initial position thus producing a normal space of two inches between staples.

In the machine of the Thompson application above referred to, staples are driven into the moving work at regular intervals. In applicant's machine provision is made to vary the distance between staples and controllably position staples at selected points in the work. This is particularly advantageous in that staples may be kept out of joints between the box sections and may be positioned in such a manner as to obtain a maximum strength with a minimum number of staples.

For varying the distances between staples and controllably positioning them at selected points in the work, mechanism is provided to controllably vary the movement of the conveyer chains 1 during the return or inoperative movement of the stapler carriage 30, thus presenting a different point on the work to the staplers for the next operation than that which would be presented normally in the operation of the machine.

As shown in Figs. 1, 2 and 3, said mechanism comprises a reciprocating pawl 49 adapted at intervals to engage and advance staple positioning blocks or lugs 50 adjustably secured in any suitable manner to a flange 51 on one of the chains 1 opposite selected fastener-receiving points on the work. Pawl 49 which rests on the flange 51 is reciprocated longitudinally of the chain and in the path of blocks 50 through a bell crank lever 52 connected to an eccentric 53 by a link 54. The construction and arrangement of the blocks 50 and pawl 49 is such that on the inoperative movement of the pawl to the right in Fig. 1, it passes over the staple positioning lugs 50 and on its operative stroke to the left in Fig. 1, it engages and pulls any such lug which may be in its path of travel. This construction and arrangement is best shown in Figs. 8 and 9. As there shown the blocks 50 are provided with bevelled surfaces 60 and the nose of the pawl is also appropriately bevelled at 61 so that when the pawl 49 encounters a block 50 on its inoperative movement to the right it rides

up over the block and snaps into operative position behind said block through the action of a spring 62 attached at one end to the pawl 49 and at the other end to lever 52. Blocks 50 may be secured to both chains 1 and a pawl 49 may be provided at either side of the machine.

The throw of the pawl 49 and the reciprocations of the stapler carriage 30 are so arranged that the pawl and the staplers move from and toward each other and meet at the time the stapler carriage starts its movement with the work. In other words, viewing Fig. 1, when the pawl 49 moves to the right the staplers move to the left thus increasing the distance between them and when the pawl 49 moves to the left the staplers move to the right thus decreasing the distance between them. The extreme throw of the pawl to the left brings it opposite the point to which the staplers are brought by the extreme throw of the carriage 30 to the right and at the time the carriage 30 is ready to start its movement to the left with the work.

In the illustrative machine the pawl 49 has a three inch throw to the right in Fig. 1 while the stapler carriage and conveyer chains are moving one inch to the left so that the pawl 49, in effect, has a four inch throw relative to the lugs 50 on the continuously moving chains 1 and when the pawl 49 is moving with the chains 1 on its drive stroke the pawl travels three inches while the chains are travelling one inch. Thus if the pawl 49 in its movement with the chains 1 encounters a lug 50 in its path, it will engage the lug and advance the chain at an increased speed and bring the point on the work opposite the engaged lug beneath the staplers at the time the staplers start their movement forward with the work. As pointed out hereinabove, the pawl and ratchet connection between gear 27 and sprocket shaft 6 permits this independent movement of the conveyer chains. The pawls 28 during such movement click idly over the teeth of the ratchet 29.

In operation the operator sets the spacer blocks 2 on flanges 3 of chains 1 in proper relationship to receive the cleats *c* and sheets *s* for the box blanks. He then determines by eye or otherwise the points relative to edges of the sections of the blanks at which he desires staples to be driven and places staple positioning lugs or blocks 50 on flanges 51 at the selected points. If he desires to position intermediate fasteners in the bodies of the sections, additional lugs 50 may be secured to the flanges 51 at the selected fastener-receiving points. In some instances the fasteners intermediate the first and last fastener of each section are spaced normal distances apart in which event the addi-

tional lugs 50 may be dispensed with. When the machine is started fasteners will be driven every two inches apart except when the pawl 49 propulsively engages a lug 50, in which event, the chains 1 will be advanced more rapidly and the point opposite the engaged lug will be presented beneath the driving point of the staplers in position to move therewith during the next fastener-driving operation. It may happen in the operation of the machine that the normal feed of the work will bring a selected fastener-receiving point on the work to fastener-receiving position, in which event the pawl 49 will not affect the feed of the work, for instance, if the point selected for a fastener happens to be just two inches behind the last fastener driven the normal feed of the work will advance said point to the staplers and pawl 49 will not perform any operation. If, on the other hand, the selected fastener-receiving point is more than two inches behind the last fastener driven, for instance, three inches behind the last fastener driven, the pawl 49 will engage the block 50 opposite said selected point and advance the work an additional inch over the normal feed. Thus it will be seen that in the illustrative machine the feed of the work during any one cycle of operation of the machine may be controlled to cause a feed movement of any distance between two and four inches, thus enabling the positioning of fasteners anywhere from two to four inches apart. It will be understood that the figures given are only illustrative and may be varied without departing from the invention.

Thus it will be seen that mechanism is provided to controllably position the driving of fasteners into continuously moving work and that this result is accomplished by varying the extent of movement of the continuously moving work during intervals between fastener-driving operations.

For clinching the staples on the under side of the work the movable carriage 30 is provided with a cross bar 55 secured to the side frames of the carriage and extending between said frames directly beneath the staplers 11 to which bar clincher blocks or anvils 56 may be adjustably secured directly beneath each stapler and upon which the staples may be driven and clinched.

For removing the completed blanks from the work-forwarding means, the machine may be provided with a table consisting of stripper bars 57 suitably supported at the delivery end of the machine, upon which table the blanks may ride and be thereby disengaged from the work-forwarding means.

Before the work is brought to the table

or stripper bars the wires connecting one blank with another may be severed by an automatic cutting mechanism 58. Said cutting mechanism is fully illustrated and described in said application of Osceola C. Thompson above referred to and therefore need not be illustrated or described in detail herein, it being sufficient to say that the cutting mechanism operates automatically to sever the wires between box blanks after a completed blank has passed the stapling plane.

Power for operating the machine may be applied in any suitable manner, for instance, by power pulley 59 shown in Fig. 3 which may be controllably clutched to the shaft 17 by any suitable clutch mechanism.

It will be understood that the expressions "continuous", "continuously" and the like, as used in the specification and claims in connection with the movement, progression or feed of the work or work-forwarding means is intended to distinguish from an intermittent or step-by-step movement, progression or feed and is intended to include any uninterrupted movement, progression or feed of the work or work-forwarding means during which the staplers operate upon the moving work.

Obviously, the present invention is not limited to the particular embodiment shown and described but may be variously embodied and the particular construction shown may be variously modified, as will appear to those skilled in the art. Furthermore, it is not indispensable that all the features of the invention be used conjointly since they may be used to advantage in various combinations and sub-combinations.

Having described the invention, what is claimed is:

1. A machine for use in making boxes comprising, in combination, means to position relatively and feed a plurality of box parts; fastener-setting mechanism operable at intervals upon moving box parts; and means controlling the movement of the box parts between fastener-setting operations to position fasteners in the box parts relative to each other or to a box part edge.

2. A machine for use in making boxes comprising, in combination, means to position relatively and feed a plurality of box parts; fastener-setting mechanism movable with the box parts during a fastener-setting operation; and means controlling the movement of the box parts between fastener-setting operations to position fasteners in the box parts relative to each other or to a box part edge.

3. A machine for use in making boxes comprising, in combination, means to position relatively and feed a plurality of box parts; fastener-setting mechanism operable

at intervals upon moving box parts; and means to vary the extent of movement of the box parts between fastener-setting operations to position fasteners in the box parts relative to each other or to a box part edge.

4. A machine for use in making boxes comprising, in combination, means to position relatively and feed a plurality of box parts; fastener-setting mechanism movable with the box parts during a fastener-setting operation; and means to vary the extent of movement of the box parts between fastener-setting operations to position fasteners in the box parts relative to each other or to a box part edge.

5. A machine for use in making boxes comprising, in combination, means to position relatively a plurality of box parts and feed them uniformly; fastener-setting mechanism operable at intervals upon moving box parts; and means to increase the extent of movement of the box parts between fastener-setting operations to position a fastener in the box parts relative to another fastener or to a box part edge.

6. A machine for use in making boxes comprising, in combination, means to position relatively a plurality of box parts and feed them uniformly; fastener-setting mechanism movable with the box parts during a fastener-setting operation; and means to increase the extent of movement of the box parts between fastener-setting operations to position a fastener in the box parts relative to another fastener or to a box part edge.

7. A machine for use in making boxes comprising, in combination, means to position relatively a plurality of box parts; means to feed the box parts continuously at a uniform speed; fastener-setting mechanism operable at intervals upon the moving box parts; and means controlling the movement of the box parts between fastener-setting operations to position fasteners relative to each other or to a box part edge.

8. A machine for use in making boxes comprising, in combination, means to position relatively a plurality of box parts; means to feed the box parts continuously at a uniform speed; fastener-setting mechanism operable at intervals upon the moving box parts; and means to vary the extent of movement of the box parts between fastener-setting operations to position fasteners relative to each other or to a box part edge.

9. A machine for use in making boxes comprising, in combination, means to position relatively a plurality of box parts; means to feed the box parts continuously at a uniform speed; fastener-setting mechanism operable at intervals upon the moving box parts; and means to increase the move-

- ment of the box parts between fastener-setting operations to position a fastener relative to another fastener or to a box part edge.
- 5 10. A machine for use in making boxes comprising, in combination, work-forwarding means to position relatively a plurality of box parts and to feed them continuously at a uniform speed; fastener-setting mechanism operable upon the moving box parts; and means automatically to vary the speed of the box-part-feeding means at selected times during the operation of the machine. 70
- 10 11. A machine for use in making boxes comprising, in combination, work-forwarding means to position relatively a plurality of box parts and to feed them continuously at a uniform speed; fastener-setting mechanism operable upon the moving box parts; and means automatically to increase the speed of the box-part-feeding means at selected times during the operation of the machine. 75
- 15 12. A machine for use in making boxes comprising, in combination, work-forwarding means to position relatively a plurality of box parts and to feed them continuously at a uniform speed; fastener-setting mechanism operable upon the moving box parts; and means automatically to control the speed of the box-part-feeding means during the operation of the machine. 80
- 20 13. A machine for use in making wire-bound boxes comprising, in combination, work-forwardly means to position relatively a plurality of box parts and feed them continuously; binding-wire-applying means including fastener-setting mechanism operable at regular intervals to drive fasteners over binding wire into the moving box parts; and means to control the extent of movement of the work-forwarding means between fastener-setting operations to position fasteners in the box parts relative to each other or to a box part edge. 85
- 25 14. A machine for use in making wire-bound boxes comprising, in combination, work-forwarding means to position relatively a plurality of box parts and feed them continuously; binding-wire-applying means including fastener-setting mechanism operable at regular intervals to drive fasteners over binding wire into the moving box parts; and means to vary the extent of movement of the work-forwarding means between fastener-setting operations to position fasteners in the box parts relative to each other or to a box part edge. 90
- 30 15. A machine for use in making wire-bound boxes comprising, in combination, work-forwarding means to position relatively a plurality of box parts and feed them continuously; binding-wire-applying means including fastener-setting mechanism operable at regular intervals to drive fas- 95
- 35 teners over binding wire into the moving box parts; and means to increase the extent of movement of the work-forwarding means between fastener-setting operations to position a fastener in the box parts relative to another fastener or to a box part edge. 100
- 40 16. A machine for use in making wire-bound boxes, comprising, in combination, binding-wire-applying means including fastener-setting mechanism operable at intervals upon moving box parts; means to position and feed box parts to said mechanism; and means to control the movement of the box parts between fastener-setting operations. 105
- 45 17. A machine for use in making wire-bound boxes comprising, in combination, binding-wire-applying means including fastener-setting mechanism operable at intervals upon moving box parts; means to position and feed box parts to said mechanism; and means to vary the extent of movement of the box parts between fastener-setting operations. 110
- 50 18. A machine for use in making wire-bound boxes comprising, in combination, binding-wire-applying means including fastener-setting mechanism movable with box parts during a fastener-setting operation; means to position and feed box parts to said mechanism; and means to increase the extent of movement of the box parts between fastener-setting operations. 115
- 55 19. A machine for use in making boxes comprising, in combination, binding-wire-applying means including fastener-setting mechanism operable at intervals; means to feed the box parts continuously to said mechanism; and means to control the movement of the box parts between fastener-setting operations. 120
- 60 20. A machine for use in making boxes comprising, in combination, binding-wire-applying means including fastener-setting mechanism operable at intervals; means to feed the box parts continuously to said mechanism; and means to vary the movement of the box parts between fastener-setting operations. 125
- 65 21. A machine for use in making boxes comprising, in combination, binding-wire-applying means including fastener-setting mechanism operable at intervals; means to feed the box parts continuously to said mechanism; and means to increase the speed of the moving box parts between fastener-setting operations. 130
- 70 22. A machine for use in making boxes comprising, in combination, binding-wire-applying means including fastener-setting mechanism operable at intervals; means to feed the box parts continuously to said mechanism; and means to control the positions of fasteners in the box parts comprising mechanism for varying the speed of the 135

- moving box parts between fastener-setting operations.
23. A machine for use in making boxes comprising, in combination, binding-wire-applying means including fastener-setting mechanism operable at intervals; means to feed the box parts continuously to said mechanism; and means to position a fastener relative to the edge of a box part comprising mechanism for controlling the speed of the moving box parts between fastener-setting operations.
24. A machine for use in making boxes comprising, in combination, binding-wire-applying means including fastener-setting mechanism operable at intervals; means to feed the box parts continuously to said mechanism; and means to control the positions of a plurality of fasteners in the work comprising mechanism for controlling the movements of the box parts between fastener-setting operations.
25. A machine for use in making boxes comprising, in combination, work-forwarding means; binding-wire-applying means including fastener-setting mechanism operable at intervals; means to feed the box parts continuously to said mechanism; and means to position fasteners at selected points in the work comprising a reciprocating actuator adapted to propulsively engage successively a series of members having connection with the work-forwarding means and located relative to selected fastener-receiving points on the work.
26. A machine for use in making boxes comprising, in combination, work-forwarding means; binding-wire-applying means including fastener-setting mechanism operable at intervals; means to feed the box parts continuously to said mechanism; and means to position fasteners at selected points in the work comprising a reciprocating actuator adapted to propulsively engage successively a series of members located relative to selected fastener-receiving points on the work and movable therewith.
27. A machine for use in making boxes comprising, in combination, work-forwarding means; binding-wire-applying means including fastener-setting mechanism operable at intervals; means to feed the box parts continuously to said mechanism; and means to position fasteners at selected points in the work comprising a reciprocating actuator adapted to propulsively engage successively a series of members correlated for movement with the work.
28. A machine for use in making boxes comprising, in combination, binding-wire-applying means including fastener-setting mechanism operable at intervals; means to feed the box parts continuously to said mechanism; and means to position a fastener at a predetermined selected point in the work comprising a member movable with the work and located relative to said fastener-receiving point and a reciprocating actuator adapted to engage said member and advance its corresponding fastener-receiving point to fastener-receiving position.
29. A machine for use in making boxes comprising, in combination, binding-wire-applying means including fastener-setting mechanism operable at intervals; means to feed the box parts continuously to said mechanism; and means to position fasteners at selected points in the work comprising a series of members movable with the work and located relative to selected fastener-receiving points thereon and a reciprocating actuator adapted during an interval between fastener-setting operations to engage one of said members and advance its corresponding fastener-receiving point to fastener-receiving position.
30. A machine for use in making boxes comprising, in combination, work-forwarding means; binding-wire-applying means including fastener-setting mechanism operable at intervals; means to feed the box parts continuously to said mechanism; and means to vary the extent of movement of the box parts between successive fastener-setting operations to position a fastener at a predetermined selected point in the work comprising a reciprocating actuator adapted to propulsively engage a member having connection with the work-forwarding means and located relative to the selected fastener-receiving point on the work.
31. A machine for use in making boxes comprising, in combination, work-forwarding means; binding-wire-applying means including fastener-setting mechanism operable at intervals; means to feed the box parts continuously to said mechanism; and means to vary the extent of movement of the box parts between successive fastener-setting operations to position a fastener at a predetermined selected point in the work comprising a reciprocating actuator adapted to propulsively engage a member movable with the work and located relative to the selected fastener-receiving point thereon.
32. A machine for use in making boxes comprising, in combination, work-forwarding means; binding-wire-applying means including fastener-setting mechanism operable at intervals; means to feed the box parts continuously to said mechanism; and means to vary the extent of movement of the box parts between successive fastener-setting operations to position a fastener at a predetermined selected point in the work comprising a reciprocating actuator adapted to propulsively engage a member located relative to the selected fastener-receiving point on the work and correlated for movement therewith.

33. A machine for use in making boxes comprising, in combination, binding-wire-applying mechanism operable upon moving box parts to position a moving binding wire thereon and fasten the same thereto; means to feed the box parts to said mechanism; and means to position fasteners in the box parts at selected points comprising mechanism to control the extent of the box part movements during the intervals between fastening operations.
34. A machine for use in making boxes comprising, in combination, binding-wire-applying means including fastener-setting mechanism operable at intervals upon moving box parts; means to feed the box parts continuously to said mechanism; and means to position a fastener at a predetermined selected point in the box parts comprising mechanism for controlling the extent of movement of the box parts during the interval between successive fastener-setting operations.
35. A machine for use in making wire-bound boxes comprising, in combination, binding-wire-applying means including fastener-setting mechanism movable with box parts during a fastener-setting operation; means to position and feed box parts to said mechanism; and means to control 30 the movement of the box parts between fastener-setting operations.
36. A machine for use in making wire-bound boxes comprising, in combination, binding-wire-applying means including fastener-setting mechanism movable with box parts during a fastener-setting operation; means to position and feed box parts to said mechanism; and means to vary the extent of movement of the box parts between fastener-setting operations.
37. A machine for use in making wire-bound boxes comprising, in combination, binding-wire-applying means including fastener-setting mechanism operable at intervals upon moving box parts; means to position and feed box parts to said mechanism; and means to increase the extent of movement of the box parts between fastener-setting operations.

In testimony whereof I have signed my name to this specification.

EDWARD F. DUNNE, JR.
